US00D645031S

(12) **United States Design Patent**
Richardson et al.

(10) **Patent No.:** US D645,031 S
(45) **Date of Patent:** ** Sep. 13, 2011

(54) **CASE**

(75) Inventors: **Curtis R. Richardson**, Fort Collins, CO (US); **Stephen Willes**, Fort Collins, CO (US)

(73) Assignee: **Otter Products, LLC**, Fort Collins, CO (US)

(**) Term: **14 Years**

(21) Appl. No.: **29/344,583**

(22) Filed: **Sep. 30, 2009**

(51) **LOC (9) CL.** **14-03**

(52) **U.S. CL.** **D14/250**

(58) **Field of Classification Search** ..... D14/138, D14/138 AA, 156, 250, 253, 440, 496; D3/201, D3/215, 218, 226, 269, 272, 273; 206/305, 206/320; 455/42, 90, 92, 575.8; D21/333; D8/25

Primary Examiner — Susan Bennett Hattan
Assistant Examiner — Barbara B Lohr

(57) **CLAIM**

The ornamental design for a case, as shown and described.

DESCRIPTION

FIG. 1 is an isometric view of a case showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line portions of the disclosure are for environmental purposes only and form no part of the claimed design.

1 Claim, 7 Drawing Sheets
